(57) **CLAIM**

We claim, the ornamental design for a liquid transfer device, as shown and described.

DESCRIPTION

FIG. 1 is a front, top perspective view of a liquid transfer device showing our design.

FIG. 2 is a rear, bottom perspective view of the liquid transfer device showing our design.

FIG. 3 is a front elevation view of the liquid transfer device of FIG. 1.

FIG. 4 is a rear elevation view of the liquid transfer device of FIG. 1.

FIG. 5 is a left side elevation view of the liquid transfer device of FIG. 1.

FIG. 6 is a right side elevation view of the liquid transfer device of FIG. 1.

FIG. 7 is a top plan view of the liquid transfer device of FIG. 1.

FIG. 8 is a bottom plan view of the liquid transfer device of FIG. 1; and,

FIG. 9. is a view of the liquid transfer device of FIG. 1 in use.

The broken lines in the drawings illustrate portions of the liquid transfer device and form no part of the claimed design.

1 Claim, 9 Drawing Sheets
